UNITED STATES PATENT OFFICE.

E LEE BREWER, OF DALLAS, TEXAS.

SAFETY-BAR ATTACHMENT FOR RAILWAY SWITCHES.

Application filed June 27, 1925. Serial No. 40,017.

To all whom it may concern:

Be it known that E LEE BREWER, a citizen of the United States, residing at Dallas, in the county of Dallas and State of Texas, has invented certain new and useful Improvements in Safety-Bar Attachments for Railway Switches, of which the following is a specification.

This invention relates to an improvement 10 in "safety bar attachment for railroad switches."

The object of the invention is to eliminate a great number of accidents which occur due to what is commonly known as 15 "splitting a switch." This is caused by the switch's failure to properly seat itself in its extreme position when it is thrown either open or closed, and subsequently a train passing over the switch point may cause the 20 latter to be thrown into the opposite direction, thus causing a derailment with often very serious results.

A further object of my invention is to 25 provide a simple and easily installed safety bar which may be easily and quickly attached to the switch point or points and when so attached it shall be automatic in nature carrying the wheels of the train into alignment with and over the points of the 30 switch even though they are not properly set.

With these objects in view, my invention 35 consists in a bar which is attached to one or more switch points and which seats itself, when the switch is closed, partly under the head of the rail but when the switch is entirely open it is spaced apart from the rail so as to allow the free passage of the trains through the switch. However, when 40 the switch has been thrown only partly closed, a shoulder on this safety bar will engage the wheels of the train and guide them into alignment with the switch point, so that the train will properly pass over 45 the switch and will automatically move the switch points into their proper positions, causing an automatic closing of the switch.

In the accompanying drawings:

Fig. 1 is a plan view of my safety bar 50 applied to a closed switch;

Fig. 2 is a similar view of a partly open switch;

Fig. 3 is a transverse section through the 55 switch and safety bar, in the position shown in Fig. 1;

Fig. 4 is a side elevation of the safety bar detached; and

Fig. 5 is a top plan view of the same.

The numerals 1 and 2 indicate the main track rails mounted on the usual cross ties 60 3. The switch points 4 and 5 of the switch are intended to be moved against the sides of the main rails 1 and 2 for guiding the train either over the main track, provided by the rails 1 and 2, and the switch point 65 5 or when the switch is thrown into the opposite open position, the train is guided over the rails 1 and 2 and switch point 4, for being directed on to the side track or another main track. The usual hand switch 70 throw is shown in the drawings but it is obvious that the device would work just as successfully with an automatic mechanism for throwing the switch. The hand operated throw, shown in the drawings, includes 75 the bar 6 which is secured to each of the switch points 4 and 5 and it has the link 7 pivoted thereto, said link being connected with the usual hand operated turn table 8, so that this switch may be thrown as desired. 80

My safety bar attachment includes the bar 9 secured by means of the bolts 10 to the switch point 5 and this bar is made to closely fit about the end of this switch 85 point 5. For this purpose, the bar is provided with a sloping top surface 11 for fitting under the head 12 of the switch point 5 and a shoulder 13 is formed on the bar 9 intermediate the ends thereof for being 90 fitted against the end of the switch point 5. The flange 14 is formed on the outer edge of the bar 9 and extends upwardly sufficiently to be engaged by the circumferential flange on the train wheels but is low enough 95 to be seated under the head of the rail 2. This flange 14 is provided with a diagonal inner surface 15 which extends from near the outer corner of the bar 9 to a point in alignment with the inner side of the switch 100 point 5, so as to guide the train wheels around the switch point 5 and through the switch.

When the switch is entirely closed, as 105 shown in Fig. 1, the safety bar is seated properly under the head of the rail 2 so as to permit the trains to pass over the main track unobstructed, and when the switch is in this closed position, the switch point 5 will be seated closely against the inner 110

surface of the rail 2, so that the flanges on the train wheels will be properly guided over the main track. However, when the switch has been accidentally or inadvertently left only partly closed, as shown in Fig. 2, there will be a slight space between the point 5 and the rail 2, which would ordinarily or at least sometimes allow the flange of the train to slip into this space between the switch point and the rail 2, and to throw the switch in the opposite direction, causing possible derailment of the train or perhaps a wreck.

My invention obviates this objection by having the bar 9 attached to the end of the switch point 5 so that when the switch is in a partly closed position, shown in Fig. 2, the diagonal side 15 of the flange 14 will engage the flanges of the train wheels guiding the same to and over the switch point 5 causing the switch to be properly closed and eliminating any possibility of derailment. When the switch is in its open position, not shown in the drawings, it is obvious that the safety bar 9 will be out of the path of the train wheels and their flanges and thus permit the train to pass unobstructed on to the side track and over the rails 1 and 2 and the switch point 4.

Thus, it will be seen that I have constructed a safety bar attachment for railway switch which will cause the point of the switch to be properly closed if they should be only partly thrown and this seating of these movable points will be maintained until subsequent manual operations.

Although I have shown my safety bar attachment as applied to only the switch

point 5, it is of course obvious that it might also be applied to the switch point 4, and would then serve the same purpose.

I claim:

1. The combination of a railway rail, and a switch point, an extension for said switch-point in position to be seated under a portion of said rail, said extension having a flange thereon provided with a diagonal inner surface in position to be engaged by the rolling stock, in the event of the switch being only partly closed for directing said rolling stock over the switch point.

2. The combination with a railway rail and a switch-rail operatively mounted relative to each other, of a safety-box attached to the said switch point in position to be seated under a portion of said rail, said bar having a flange thereon provided with a diagonal inner surface in position to be engaged by the rolling stock in the event of the switch being only partly closed for directing said rolling stock over the switch point.

3. A combination with railway rails and a switch having switch points and means for closing said switch, of a safety bar attached to one of the switch points in position to be seated under a portion of one of the rails, said bar having a flange thereon provided with a diagonal inner surface in position to be engaged by the railway rolling stock, when the switch is partly closed for directing said rolling stock over the switch point, and automatically closing the switch.

In testimony whereof I affix my signature.

E LEE BREWER.
